[57] CLAIM

The ornamental design for a solar powered ventilating fan for welding helmets, as shown and described.

DESCRIPTION

FIG. 1 is a front elevational view of a solar powered ventilating fan for welding helmets showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a top perspective view thereof, and

FIG. 8 is a bottom perspective view thereof.
